United States Patent Office.

FRANCIS CAFFREY AND JOHN L. NETTLETON, OF WEST CHESHIRE,
CONNECTICUT.

Letters Patent No. 91,082, dated June 8, 1869.

IMPROVED MACHINE FOR MILLING THE BODY OF KEYS.

The Schedule referred to in these Letters Patent and making part of the same.

To all whom it may concern:

Be it known that we, FRANCIS CAFFREY and JOHN L. NETTLETON, of West Cheshire, in the county of New Haven, and State of Connecticut, have invented a new Improvement in Machine for Milling Keys; and we do hereby declare the following, when taken in connection with the accompanying drawings, and the letters of reference marked thereon, to be a full, clear, and exact description of the same, and which said drawings constitute part of this specification, and represent in—

Figure 1, a side view;

Figure 2, a top view; and in

Figure 3, a sectional view enlarged.

The object of this invention is the construction of a machine for "milling keys," that is, for turning or finishing the key between the bow and the bit.

This has heretofore been performed by fixing the bit in the mandrel, which imparts a revolving motion to the key; but in that process the milling turns or twists the key more or less, so that it is necessary, after the key is milled, to straighten or twist it back, so that the eye and bit are in the proper relative position to each other.

By our invention, this difficulty is entirely overcome, and consists in the arrangement of two mandrels, the axes of which are in line with each other, and caused to revolve together, the one holding the key by the bit, the other by the eye, thus turning the key by both ends, and this combined with the dies for milling the key.

To enable others skilled in the art to construct and use our improvement, we will proceed to describe the same as illustrated in the accompanying drawings.

A. is the bed of the machine, supporting, at their opposite ends, mandrels B and C, in their respective bearings *b* and *c*, the mandrel B being fixed, the mandrel C arranged so as to slide toward and from the mandrel B, by means of a handle, D, or otherwise.

E, the driving-shaft, extends the length of the ma-

chine, and communicates to both mandrels a corresponding revolution, through gears F F on the shaft, working into pinions *f* on the respective mandrels, so that both mandrels revolve in the same direction, and with equal velocity. The mandrel B is constructed to receive the bit of the key, as seen in fig. 3; the other mandrel, C, so as to hold the eye, as also seen in fig. 3.

On a transverse way, H, two mills, I I, are arranged, so that by the turning of a right-and-left screw, *h*, the two mills are drawn together or forced asunder. The mills are cut so as to give to the key the desired form, as seen in fig. 3.

The mills being open, as seen in fig. 2, the mandrel C is drawn back, as denoted in red, fig. 1, the bit of the key inserted in the mandrel B; then the mandrel C returned, so as to take the eye, as seen in fig. 3; then the two mandrels caused to revolve, and the two dies brought up to the key cut the stem of the key into a corresponding form. This is all done at a single operation, and in very much less time than can be done by the ordinary process.

By this machine, the mills or dies are cut at a very small expense, inasmuch as it is only necessary to make a "cherry" of the form of the key-stem, place it in the two mandrels, and the blanks for the mills in position, and force them against the "cherry," and they are cut to the desired form.

Having fully described our invention,

What we claim as new and useful, and desire to secure by Letters Patent, is—

The combination of the two mandrels B and C, revolving together, and constructed so as to receive and hold the key, with the mills I I, the whole constructed and operating substantially in the manner set forth.

FRANCIS CAFFREY.
JOHN S. NETTLETON.
